UNITED STATES PATENT OFFICE.

HENRY E. BAST, OF LAWLER, IOWA.

VULCANIZING DEVICE.

1,206,799.

Specification of Letters Patent. Patented Dec. 5, 1916.

Application filed March 28, 1916. Serial No. 87,325.

To all whom it may concern:

Be it known that I, HENRY E. BAST, a citizen of the United States, residing at Lawler, in the county of Chickasaw, State of Iowa, have invented certain new and useful Improvements in Vulcanizing Devices; and I do hereby declare the following to be a full, clear, and exact description of the invention, such as will enable others skilled in the art to which it appertains to make and use the same.

This invention relates to improvements in vulcanizing devices.

The principal object of the invention is to provide a simple and cheap device for repairing rubber boots.

Another object is to provide a novel and efficient device of this character whereby any part of the sole and heel or upper can be quickly and easily vulcanized.

Other objects and advantages will be apparent from the following description when taken in connection with the accompanying drawing.

In the drawing: Figure 1 is a side elevation of my improved boot vulcanizer; Fig. 2 is a similar view showing a boot applied to the device and the parts in the position assumed while the vulcanizing process is in progress; Fig. 3 is a top plan view of the device in the position of Fig. 2; Fig. 4 is a transverse section on the line 4—4 of Fig. 3; Fig. 5 is a transverse section on the line 5—5 of Fig. 1; Fig. 6 is a side elevation showing the device adjusted for vulcanizing the instep of the boot; Fig. 7 is a front elevation of the device when used in vulcanizing the side of the boot.

Referring particularly to the accompanying drawing, 10 represents a vertical standard, the lower end of which is pivotally connected to an arm 11 by means of a bolt 12, which arm is in turn pivotally adjustable on a clamp 11 by means of a clamping bolt 11, said clamp being adapted to be engaged with the edge of the work bench 12. On the upper end of the standard is mounted a foot form or last 13. This last is adjustably mounted on the upper end of the standard so that it can be rotated to any desired position, both the last and the standard having the teeth 14, and the parts being held in adjusted positions by a screw 15, the upper

end of which is countersunk into a recess 15' in the heel of the last.

Pivottally mounted on the lower end of the standard is an arm 16 adapted to swing in a plane at right angles to the standard and having a longitudinally extending slot formed in the outer portion thereof, as shown at 17. This slot extends through the outer end of the arm for a purpose which will appear later. A nut 18 has grooves 19 formed in two of its opposite faces, and this nut is slipped into the slot 17 so that the side walls of the slot enter the grooves of the nut. A set screw 20 is engaged through the nut, and carries detachably on its inner end a former block 21. This former block is arranged to be pressed against the side of the boot 22 in the act of vulcanizing. The outer face of the former block is provided with a cup-shaped recess 23 which is adapted to be filled with gasoline and then lighted to produce the required amount of heat to accomplish the vulcanization.

For use in vulcanizing the sole and heel or the sides and top of the upper of the boot, I attach an angle plate 24 to the screw 20 by means of a nut 25, so that the angle plate can be turned on the screw to various angles. The outstanding portion of the angle plate is formed with a longitudinally extending and open-ended slot 26, in which is slidably disposed a nut 27, similar in construction to the before-mentioned nut, and carrying a set screw 28. This screw is adapted to carry a former block in the same manner as the before-mentioned screw.

What is claimed is:

1. A vulcanizing apparatus for boots comprising an adjustably rotatable lasting jack for supporting a boot, and a movably adjustable vulcanizing former member carried by the jack.

2. A vulcanizing apparatus for boots comprising an adjustably rotatable lasting jack, an arm rotatably adjustable on the jack and a vulcanizing former block slidably and rotatably adjustable on the arm.

3. A vulcanizing apparatus for boots comprising an adjustably rotatable lasting jack, a longitudinally slotted arm rotatably and adjustably mounted on the jack, and a vulcanizing former block slidably and rotatably adjustable in the slotted arm.

4. A vulcanizing apparatus for boots comprising an adjustably rotatable lasting jack, a longitudinally slotted arm rotatably and adjustably mounted on the jack, a slotted angle member slidably and rotatably adjustable in the slot of the arm, a vulcanizing former block slidably and rotatably adjustable in the angle member, and means for

forcing the block against the rubber to be vulcanized. 10

In testimony whereof, I affix my signature, in the presence of two witnesses.

HENRY E. BAST.
